DESCRIPTION

U.S. PATENT DOCUMENTS

FIG. 1 is a top front right perspective view of a combined stabilizer, flash hider, and recoil reducer device for firearms, showing our new design;

1,636,357 A * 7/1927 Cutts, Jr. F41A 21/36
89/14.3
D268,861 S 5/1983 Gwinn, Jr.
D285,238 S 8/1986 Cellini
D296,350 S 6/1988 Cellini
4,813,333 A * 3/1989 Garris F41A 21/38
89/14.3
D417,252 S * 11/1999 Kay D22/100
D613,814 S * 4/2010 Farina D22/116
D682,384 S * 5/2013 Jaureguizar D22/108

FIG. 2 is a bottom rear left perspective view thereof; FIG. 3 is a right side elevation view thereof, with the left side elevation view being a mirror image thereof;

FIG. 4 is a top plan view thereof;

FIG. 5 is a bottom plan view thereof;

FIG. 6 is a rear elevation view thereof; and,

FIG. 7 is a front elevation view thereof.

The broken lines define the bounds of the claimed design and form no part of the claimed design.

The unshaded area between broken and solid line forms no part of the claimed design.
